(57) **CLAIM**

The ornamental design for vehicle-wheel front face, as shown and described.

DESCRIPTION

FIG. 1 is a perspective view of a vehicle-wheel front face according to my new design;

FIG. 2 is a front elevational view thereof;

FIG. 3 is a front elevational view of a second embodiment of my design wherein the front face is rotatable with respect to a rim of the wheel; and,

FIG. 4 is a side elevation of FIGS. 2 and 3.

Portion of the wheel depicted in broken lines are for illustrative purposes only, and form no part of the claimed design.
